UNITED STATES PATENT OFFICE.

EUGENE E. KELLEY, OF GREENSBURG, PENNSYLVANIA.

NOISELESS PIVOT-HINGE.

1,026,750.

Specification of Letters Patent.

Patented May 21, 1912.

Application filed July 18, 1911. Serial No. 639,141.

To all whom it may concern:

Be it known that I, EUGENE E. KELLEY, a citizen of the United States, and a resident of Greensburg, county of Westmoreland, State of Pennsylvania, have invented certain new and useful Improvements in Noiseless Pivot-Hinges, of which the following is a specification.

My invention relates broadly to builders' hardware and more specifically to a noiseless universal joint or hinge particularly adapted for the suspension of oscillating bodies.

The principal object of my invention is to provide a noiseless universal joint adapted to act as a connecting member for ends of supports particularly adapted to support porch swings and swinging chairs.

Another object of my invention is to provide a universal joint with pivots at right angles to each other, one of said pivots being free to swing upon its axis, the other of said pivots being frictional, thus tending to resist movement upon its particular axis.

A further object of my invention is to provide a terminal member for supports of chains or other suspension devices, particularly adapted for the suspension of porch swings and the like, which terminal member includes a wooden journal block forming the pivot of major oscillation.

Other and further objects of this invention will in part be obvious and will in part be pointed out with more particularity by reference to the accompanying drawings and specific description hereinafter following.

Referring more particularly to the drawings in which like characters represent like numerals throughout the various figures thereof: Figure 1 is a perspective view of my invention as applied to a ceiling attaching block and supporting member. Fig. 2 is a detail in partial section illustrating my invention as applied to the lower journal block as attached to the chair or swing frame. Fig. 3 is a detail of one form of the wooden block. Fig. 4 is a detail of one form of the inclosing strap. Fig. 5 is a perspective view illustrating my invention as applied to a porch swing.

In swinging chairs and porch swings wherein the seat of the swing or chair is usually supported from an overhead beam or ceiling by means of chains, it becomes

desirable that the journal blocks forming the end attachments of the chain, both to the overhead support and to the seat of the chair *per se*, shall be so constructed as to obviate unpleasant squeaking noises. Furthermore, it is particularly desirable that the support may have a free movement in a fore and aft direction with reference to the front and back of the swing or support, while the movement in a sidewise direction which is at right angles to the fore and aft direction, be more or less restricted. In other words, it is desirable that the supporting chains be so arranged as to swing freely back and forth and not to swing so freely in a sidewise direction.

My invention, as will be more specifically described hereinafter, cooperates as well with rigid supporting bars or rods, as with flexible chains, or ropes.

Referring more particularly to the drawings, my invention comprises an attaching member which may be a screw eye 1, as disclosed in Fig. 1, or an eye bolt 2, as disclosed in Fig. 2. The eye portion 3 of the screw eye or bolt, is secured between the inclosing strap 4 by means of a pivot bolt or rivet 5, which passes through openings 6 in the inclosing strap. The pivot bolt or rivet 5 is preferably tightened down upon the eye portion 3 of the eye bolt in such manner as to cause a considerable degree of friction between the side walls of the inclosing strap 4 and the eye portion of the supporting bolts 1 and 2. The inclosing strap 4 tightly clamps a resilient journal block 7, preferably formed of wood, which is provided with a journal opening 8, and is preferably formed upon its exterior with a partial circumferential rib 9. The inclosing strap 4 is provided on its exterior surface with a raised rib 13 which is adapted to cooperate with the circumferential rib 9 on the journal block to prevent the journal block being displaced endwise from the supporting strap. The wooden journal block 7, may if desired, be flattened as at 10, in order to permit the screw eye 3 to be properly positioned between the ends of the inclosing strap 4. The journal opening 8 in the wooden block 7 is preferably located near the flattened portion 10, which flattened portion is adjacent the open ends of the strap 4, thereby permitting a greater amount of wood between the lower portion of the supporting

strap and a pivot journal, which will hereinafter be more specifically described. An attaching loop 11 terminates in eye portions 12, which form bearing heads for retaining 5 a journal member 14, that may comprise a rivet or bolt, which passes loosely through the journal opening 8 in the wooden block.

Referring more particularly to Fig. 5, upper supporting members 15, with a screw 10 eye member, as is illustrated in Fig. 1, are screwed into an overhead beam 16, while the lower supporting members 17 are fixedly attached to the seat frame of a swinging chair 18. The overhead supporting members 15 are connected to the seat supporting members 18 by chains 19. As has been hereinbefore stated, any other type of securing means, for example, rigid bars or ropes, may be used in place of the chains 20 illustrated.

In operation, as the chair seat or swing frame is oscillated back and forth with a swinging movement, the pivot journal 14, which is at right angles to the line of 25 oscillation, permits of the free movement of the chair back and forth, while the pivot bolt or rivets 5, whose axes are in line with the to and fro motion of the swing, tend to prevent any endwise movement of the 30 swing to a certain extent by reason of the

friction interposed between the screw eye 3 and the strap 4, as hereinbefore stated. It will be noted that the journal block 7, which is preferably formed of wood, 35 cooperates with the journal member 14, and as this particular bearing is utilized the major portion of the time during the normal oscillation of the swing, the disagreeable squeaking so common in porch swing supports, is entirely obviated because of the 40 noiseless coöperation of the metal and wood bearing described.

Having thus described my invention what I desire to claim is:—

A noiseless pivot hinge comprising a bearing block of yielding material having a peripheral ridge, a continuous retaining strap encircling said bearing block and provided with a longitudinal groove adapted to register with the peripheral ridge of the block, 45 an eye bolt pivoted between the ends of the retaining strap so as to permit its oscillation transverse the block, a journal member loosely mounted in the block, and an attaching loop secured to the extremities of the 50 journal member.

EUGENE E. KELLEY.
